GLASSWASHER TRAY

Robert E. Newman, Berkeley, Calif.

Application May 16, 1949, Serial No. 2,695

Term of patent 7 years

(Cl. D49—1)

To all whom it may concern:

Be it known that I, Robert E. Newman, a citizen of the United States, residing at Berkeley, in the county of Alameda and State of California, have invented a new, original, and ornamental Design for Glasswasher Tray, of which the following is a specification, reference being had to the accompanying drawing, forming part thereof.

Fig. 1 is a top plan view of a glasswasher tray showing my new design.

Fig. 2 is a front elevation,

Fig. 3 is a side elevation, and

Fig. 4 is a section taken on line 4—4 of Fig. 1 showing my new design.

I claim:

The ornamental design for a glasswasher tray, as shown.

ROBERT E. NEWMAN.
